W. WEST.
WATER CLOSET FOR RAILWAY CARRIAGES.
APPLICATION FILED APR. 10, 1912.

1,112,507.

Patented Oct. 6, 1914.

UNITED STATES PATENT OFFICE.

WILLIAM WEST, OF DENVER, COLORADO.

WATER-CLOSET FOR RAILWAY-CARRIAGES.

1,112,507.

Specification of Letters Patent.

Patented Oct. 6, 1914.

Application filed April 10, 1912. Serial No. 689,856.

To all whom it may concern:

Be it known that I, WILLIAM WEST, a citizen of the United States, residing at Denver, in the county of Denver and State of Colorado, have invented certain new and useful Improvements in Water-Closets for Railway-Carriages, of which the following is a specification.

My invention relates to water-closets for railway carriages, and its object is to provide a construction which will adapt the closet for use at all times, whether the car is in motion between stations, standing still at a station, or passing through a town or city.

Nearly all municipalities along the line of a railroad have established ordinances by which the railway companies are compelled to lock the doors of the water closets on their cars, while a train is moving within the limits of the municipality or standing at a station, and it is obvious that this closing of the closets is of great inconvenience to the passengers, especially when the car or train is delayed a long time at a station.

By the use of my invention the railroad companies may avoid all danger of violating the ordinances above referred to, and the passengers on their trains will at no time be denied access to the closets.

My invention consists with this end in view, in providing a receptacle which may be adapted from a point within the car, and preferably outside the compartment in which the closet-bowl is installed, to retain the matter passing through the outlet of the bowl. This receptacle is of sufficient size to receive this matter during a considerable length of time, and it is constructed to immediately discharge its contents when desired.

Means are provided to effectively prevent the emanation of odor from the contents of the receptacle into the car, a simple contrivance is applied to the receptacle to prevent freezing of matter contained therein, and a valve-controlled water-pipe is connected to flush the receptacle for the purpose of expediting the discharge of its contents and thoroughly cleaning its walls after the car to which it is applied has left a station.

An embodiment of my invention is shown in the accompanying drawings in the various views of which like parts are similarly designated, and in which,

Figure 1 represents a side elevation of a railroad carriage, partially in section to which my invention is applied. Fig. 2, a vertical section taken along the line 2—2 Fig. 1, and, Fig. 3, a fragmentary sectional view of the receptacle in which the matter discharged from the closet-bowl is deposited.

Referring more specifically to the drawings, the reference numeral 2 designates a railroad carriage provided with a compartment or closet 3 in which the bowl 4 is installed. The bowl is, as usual, provided with a hinged seat 5 and it has an outlet-pipe 6 which extends through an opening in the floor of the carriage.

A tank 7 is securely fastened beneath the floor of the carriage to receive matter discharged from the bowl 4 and the bottom of this tank slopes toward a discharge-pipe 8 located at one of its ends in axial alinement with the outlet of the bowl.

A vent-pipe 9 extends from the tank to a point adjacent the roof of the carriage for the escape of gases, and a valve-controlled connection 10 is adapted to connect the tank with a conveniently located source of water, to flush the same whenever desired.

The outlet 6 of the closet-bowl is normally closed by means of a flap-valve 12, which, when the seat of the bowl is unoccupied, is maintained in its closed position by the action of a spring 13 upon the arm of a lever 14, which by means of a push-rod 15 is connected with a crank-arm 16 on the valve.

A plunger 17 pivotally connected with the lever 14 extends loosely through an opening in the rim of the bowl to be engaged by the seat 5, so that the weight of an occupant thereof will cause a movement of the lever about its fulcrum and a consequent opening movement of the valve 12, which by means of the spring is returned to its normal closing position the moment the bowl seat is relieved from the weight of its occupant.

The discharge-pipe 8 of the receptacle 7 is likewise provided with a valve 18 whose crank-arm 19 is by means of a rod 20 connected with a lever 21 which is fulcrumed, as at 22, outside the compartment 3, whereby the position of the valve may be adjusted by the attendant of the car without entering the closet.

To prevent freezing of the contents of the tank, I have provided a pipe 23 which is

coiled around the discharge pipe 8, and which may connect with the boiler of the locomotive to which the carriage is attached, or with any other suitable source of calciferous fluid.

The outlet 6 of the bowl 4 is normally closed by the valve 12 to be opened only when the seat 5 is occupied, but the discharge-pipe 8 of the tank 7 is closed only when the carriage is standing still or is moving within the limits of a municipality. In such a case, the attendant of the carriage closes the valve 18 by manipulation of the lever 22 and the matter deposited in the closet bowl which otherwise would pass through the alined openings 6 and 8 directly onto the ground, is now retained in the tank 7.

Inasmuch as the bowl-outlet is immediately closed when the occupant of the closet rises from the seat, and as the gases emanated from the contents of the receptacle, escape through the vent-pipe 9, no odor will be perceptible in the carriage even though the said contents be retained during a considerable length of time.

The fluid passing through the pipe 23 will effectively prevent freezing of matter contained in the tank and when, after the car-

riage has left a station, the valve 18 is re-opened, the receptacle 7 may be instantly flushed and thoroughly cleaned by connecting the plug 10 with a source of water and opening its valve.

Having thus described my invention what I claim and desire to secure by Letters-Patent is:—

In a water closet for railway carriages, a tank having a sloping bottom, a single vertically, downwardly extending outlet conduit which is disposed at the lower end of said bottom, and an inlet opening disposed above and in axial alinement with said conduit for the connection of the tank with the outlet of a closet bowl in a railway carriage beneath which it is applied, an outwardly opening valve at the lower end of said conduit, means for moving said valve from a point within the said carriage, and means at the end of the tank remote from said conduit for its connection with a source of water supply.

In testimony whereof I have affixed my signature in presence of two witnesses.

WILLIAM WEST.
